DESIGN FOR AN AUTO COMPASS

Burl E. Sherrill, Peru, Ind.

Application March 6, 1941, Serial No. 99,376

Term of patent 14 years

To all whom it may concern:

Be it known that I, Burl E. Sherrill, a citizen of the United States and a resident of Peru, in the county of Miami and State of Indiana, have invented a new, original, and ornamental Design for an Auto Compass, of which the following is a specification, reference being had to the accompanying drawing, forming a part thereof, and in which:

Fig. 1 is a perspective view of an auto compass showing my new design;

Fig. 2 is a front elevational view of the same; Fig. 3 is an elevational view of the same showing the side opposite to that seen in Fig. 1;

Fig. 4 is a view of the top of the same as seen from above in Fig. 2; and

Fig. 5 is a view of the bottom of the same as seen from below in Fig. 2.

I claim:

The ornamental design for an auto compass, as shown.

BURL E. SHERRILL.
